UNITED STATES PATENT OFFICE.

JOHN A. K. MCGREGOR, OF NEW YORK, N. Y., ASSIGNOR TO HIMSELF,
HERMAN COHN, EDWARD COHN, HENRY WALLACH, AND SOLOMON
J. WALLACH, TRUSTEES, ALL OF SAME PLACE.

ELECTRIC SWITCH.

SPECIFICATION forming part of Letters Patent No. 439,602, dated October 28, 1890.

Application filed May 6, 1890. Serial No. 350,789. (No model.)

To all whom it may concern:

Be it known that I, JOHN A. K. MCGREGOR, a citizen of the United States, and a resident of New York, in the county of New York and

5 State of New York, have invented a certain new and useful Improved Electrical Switch, of which the following is a specification, reference being had to the accompanying drawings, forming part of the same, in which—

10 Figure 1 is a plan view of a single-pole switch embodying my invention with the slide in such position that the circuit is broken.

Fig. 2 is a plan view with the slide in a second position intermediate the first and that 15 when the circuit is closed. Fig. 3 is a vertical longitudinal sectional view on line xx , Fig. 2. Fig. 4 is a plan view of the switch with the circuit closed. Fig. 5 is a vertical longitudinal sectional view on line yy , Fig. 15

20 Fig. 6 is a vertical cross-sectional view on line zz , Fig. 5. Fig. 7 is a plan view of a modified form of the switch in the second position. Figs. 8 and 9 are sectional views of still other modified forms of the switch, the 25

first having the wing pivoted instead of rigidly secured to the slide and the second having the wing flat and the inclined plane secured to the terminal arm. Fig. 10 is a plan view of the modification adopted when a double- 30

pole switch is required; Fig. 11, a plan view of that employed for an arc-lamp line, the current being cut off from some one arc; and Fig. 12 a similar view showing the arrangement when the particular division controlled 35 by the switch is cut in.

The difficulty with most single-pole switches used for the connections of incandescent lights is that they do not indicate when the current is on and when it is off. Again, if a 40 part breaks, it may so fall as to complete the circuit, and the current cannot be cut off without taking the switch apart with a constant danger in so doing, and, being composed of at least seven parts, it is expensive to make.

45 My switch is simple, inexpensive, and not liable to break, but so arranged that if it should the current will almost certainly be cut off. Furthermore, its arrangement is such that it readily indicates when the circuit is

closed and when broken, and its form such 50 in that it may be more conveniently placed in an inconspicuous position than those in use in Figs. 1 and 9.

I show it as adapted for a single-pole switch; but it may be readily altered to make a double-pole switch, as shown in Fig. 10, or an arc-lamp-line switch, as shown in Figs. 11 and 12. As shown, it consists of a box B, in the bottom of which there is a dovetailed groove g. Near one end there is preferably arranged 55 a pillow-block b, and it is provided with a cover C. It is usually made of wood, and being rectangular in form the cover may be made to conform to the style of a window-frame or other molding upon which it is to 60 be placed, and the box being let into the wood-work the cover makes a part thereof, and nothing appears except the thumb-piece of the slide and the slot in which it may move; but porcelain would answer equally 65 well, or even metal, if block b were an insulator and the wires made no electrical contact with the box.

In groove g, I seat a slide S. It has a thumb-piece t, a bridge b', two inclined planes p, secured to the main body of the slide, and inclined shoulders s, all parts but the bridge being preferably non-conductors. One plane p might be omitted, as will be shown.

Secured to block b and extending well forward are two contact-pieces d d', with offsets at the free ends, usually brass leaf-springs, their said free ends being arranged to normally rest in a plane a little below the level of the lower ends of planes p, and with 80 the ends secured upon block b separate wires w w' are electrically connected. These contact-pieces might be simple strips extending directly inward from the sides of the box and without offsets; but as arranged a greater 85 length of spring is more conveniently permitted.

The operation of the switch is as follows: The parts being in the position shown in Fig. 1, it is desired to close the circuit. Then the 90 thumb-piece is seized and the slide moved toward the other end of the groove g' in the cover. Planes p pass under the offset ends of

d d' and raise them up, as seen in Figs. 2 and 3. As *S* moves on these pieces pass off the rear ends of planes *p* and fall upon bridge *b'*, and the contact is complete from one wire *w*, 5 through one piece *d*, the bridge *b'*, and the other piece *d'*, to wire *w'*. To break the circuit, the slide is moved back, pieces *d d'* pass off bridge *b'*, but under planes *p*, their rear ends being higher than bridge *b'*, and the circuit is broken. If at this moment the movement of the slide were reversed, still the circuit would remain broken, for the normal position of the free ends of pieces *d d'* is lower than bridge *b'*, and the non-conducting shoulders *s*, with their downward and backward inclination, would be first to engage pieces *d d'* and would force them still lower. It therefore follows that before the circuit can be again closed slide *S* must be returned to its 15 first position, in doing which planes *p* will force down and ride over the free ends of pieces *d d'*, which will then rise above the level of the lower ends of said planes, and the switch is again in position to be operated to close 20 the circuit. It therefore follows that the circuit will seldom be accidentally closed, for if not returned to the first position the slide cannot close the circuit at all, and if so returned sufficient force must be employed to 25 force pieces *d d'* up sufficiently to let planes *p* pass under them and to carry the slide far enough to permit them to fall upon the bridge *b'*.

In Fig. 7, as is manifest, but one plane *p* is 30 employed, its operation being as already described. On the other side of slide *S* there is no wing, and piece *d'* rests continuously upon bridge *b'*.

Of course pieces *d d'* might be pivoted so 35 as to act merely by gravity, but the contact made would not be so perfect as when they are in the form of springs. Planes *p*, instead of being part of the body of slide *S*, might be wings pivoted thereto, as shown by Fig. 8, or 40 the combination might be reversed and the plane placed upon the contact-pieces and flat wings placed upon the slide, as shown by Fig. 9, without departing from the spirit of the invention; but the arrangement shown is the 45 one I prefer, and especially the relative dimensions of the parts, which insure that when the slide is near the farther extremity of the box the circuit is closed and when near the center it is broken. This can easily be remembered, or an indicator may be placed beside groove *g'*.

The modification shown in Fig. 10 will be 50 readily understood, the only changes being in having four contact-pieces instead of two and arranging the wings to release them all at the same moment, providing also that the bridge shall extend so as to receive the ends of each set as they fall and dividing it into two sections *b'* and *b''*, insulated from each other by 55 strips *i'*, one of which sections *b'* will bridge the circuit from terminal *d* to *d'*, and the other *b''* will bridge that from terminal *d''* to *d'*.

In Figs. 11 and 12 the slide is extended at the front and has conducting-strips *c* upon the wings, but insulated from each other, and 70 insulated from the bridge also, by narrow strips *i*, (shown by heavy black lines,) usually at some point of the inclined plane made narrower than the ends of the contact-pieces and exactly at the same relative distance 75 from the respective ends of said pieces. *w w'* are intended to represent the wires of some particular lamp, and *W W'* the main-line conductor.

When the switch is in the position shown 80 in Fig. 11, it will be noticed that the circuit from *W* to *W'* is completed through bridge *b'* direct, but no current reaches *w w'*. Now, if the slide is moved to the position shown in Fig. 12 the contact-pieces *d d'* ride over the 85 planes, cross insulations *i*, and rest on strips *c*, and the circuit is from *W* through *d' c d'' w'*, lamp *w d'' c d W'*, as is desired, and, as stated, *d d'* being wider than *i*, made contact with *c* before they broke contact from the bridge-extensions on the planes, and there was therefore no sparking, as would otherwise have been the case.

What I claim as my invention, and desire to secure by Letters Patent, is—

1. In an electrical switch, the combination 95 of two contact-pieces, a slide carrying a bridge and a wing, and an inclined plane arranged in a line drawn parallel to the line of movement of said slide and through said wing and the free end of the adjacent contact-piece, secured, as described, so that when said slide is moved in one direction until a line drawn at right angles to its line of movement will pass through the contact-piece, the wing, and the inclined plane said wing will be at one 100 side of said piece and of the inclined plane, a portion of said plane will be between a portion of said wing and the contact-piece, and all will be in contact, and when moved farther the contact-piece will engage the bridge, all substantially as set forth.

2. In an electrical switch, the combination 105 of two contact-pieces, a slide carrying a bridge and a wing, and an inclined plane arranged in a line drawn parallel to the line of movement of said slide and through said wing and the free end of the adjacent contact-piece, secured, as described, so that when said slide is moved in one direction until a line drawn at 110 right angles to its line of movement will pass through the contact-piece, the wing, and the inclined plane said wing will be at one side of said piece and of the inclined plane, a portion of said plane will be between said wing 115 and the contact-piece, and all will be in contact, but when moved in the opposite direction from its limit of motion until it reaches the position aforesaid said wing will be at the other side of said piece, all substantially 120 as set forth.

3. In an electrical switch, the combination 125 of two contact-pieces, a slide carrying a bridge, and an inclined plane located in front of said

bridge, one end higher and the other lower than it and lower than the normal position of the free end of the adjacent contact-piece, which is itself normally lower than the plane of the bridge, substantially as set forth.

4. In an electrical switch, the combination of two contact-pieces, a slide carrying a bridge, an inclined plane located in front of said bridge, one end higher and the other lower than it and lower than the normal position of the free end of the adjacent contact-piece, which is itself normally lower than the plane of the bridge, and an inclined shoulder placed below said bridge, substantially as set forth.

10 5. In an electrical switch, the combination of two contact-pieces with a space between their free ends, a slide with a body narrower than said space, adapted to move between

said ends, inclined planes of greater dimensions than the space between the sides of the 20 slide and the adjacent ends of the contact-pieces and at one end higher and the other lower than said free end, and a bridge secured to said slide beyond said planes, of greater length than the space between the free ends 25 of said contact-pieces and at a level higher than the normal position of said free ends, substantially as set forth.

Signed at New York, in the county of New York and State of New York, this 3d day of 30 May, A. D. 1890.

JOHN A. K. McGREGOR.
